DESIGN FOR A COMBINED VENDING CONTAINER AND TRAY

Jack R. Stone, Oklahoma City, Okla.

Application November 25, 1939, Serial No. 88,476

Term of patent 3½ years

To all whom it may concern:

Be it known that I, Jack R. Stone, a citizen of the United States, residing at Oklahoma City, in the county of Oklahoma and State of Oklahoma, have invented a new, original, and ornamental Design for a Combined Vending Container and Tray, of which the following is a specification, reference being had to the accompanying drawing, forming part thereof.

Referring to the drawing:

Figure 1 is a side perspective view of a combined vending container and tray showing my new design;

Figure 2 is a fragmentary perspective view taken from the opposite side of the container with the cover shown in Figure 1 removed.

Figure 3 is a fragmentary perspective view taken from the front of the container;

Figure 4 is a top plan view of the container; and

Figure 5 is a sectional view taken along the line 5—5 of Figure 1.

I claim:

The ornamental design for a combined vending container and tray, as shown.

JACK R. STONE.
